Patented Dec. 13, 1921.

FIG. 1.

FIG. 2.

Inventor
Charles T. Stewart.

By his Attorneys
Edgar V. St. Hilaire.

UNITED STATES PATENT OFFICE.

CHARLES T. STEWART, OF SCOTCH PLAINS, NEW JERSEY.

GAME DEVICE.

1,399,818.

Specification of Letters Patent. Patented Dec. 13, 1921.

Application filed February 4, 1921. Serial No. 442,360.

To all whom it may concern:

Be it known that I, CHARLES T. STEWART, a citizen of the United States, and residing at Scotch Plains, in the county of Union and 5 State of New Jersey, have invented certain new and useful Improvements in Game Devices, of which the following is a specification, such as will enable those skilled in the art to which it appertains to make and use

10 the same.

This invention relates to game devices, and the object thereof is to provide an improved device of this class by which a game interesting and attractive both to young and 15 old may be played; and with this and other objects in view the invention consists in a device of the class specified, constructed as hereinafter described and claimed.

The invention is fully disclosed in the following specification, of which the accompanying drawing forms a part, in which the 20 separate parts of my improvement are designated by suitable reference characters in each of the views, and in which:

25 Figure 1 is a plan view showing one form of my improved game device;

Fig. 2 a side view thereof; and,

Fig. 3 a central longitudinal section through the device but showing a modification.

In the practice of my invention, as shown in Figs. 1 and 2, I provide a main body portion *a* having a handle *a*², and this body portion *a* with its handle *a*² is made in the 35 form of an ordinary tennis racket, the part *a* being of substantially or approximately elliptical form and having an interior open or network *a*³. Mounted on the body portion *a* of the device is a ball cage member, in the construction 40 comprising a top part *b* and legs *b*² and forming in connection with the body portion *a* a complete ball cage adapted to receive and hold a ball *c*. The top part *b* of the ball cage member, in the construction 45 shown, is composed of wire and fashioned to form four corner circular portions *b*³ and a central circular portion *b*⁴ through which the ball *c* is adapted to pass, and these parts form in connection with the 50 body *a* five separate ball receiving receptacles or chambers in the construction shown. The legs *b*² are rotatably connected with the part *b* and are provided near the lower ends thereof with yoke-shaped parts *b*⁵ provided 55 at their lower ends with leg portions *b*⁶ having set screws *b*⁷ by means of which the cage

member may be detachably connected with the body *a*, as clearly shown in Fig. 2, and the legs *b*² are rotatably connected with the part *b* and may be folded inwardly as indicated in dotted lines in Fig. 2 so that the entire cage portion of the device with the exception of the body *a* may be compactly folded and laid on, or placed in said body, for convenience in transportation, carrying 60 about, or shipping.

In Fig. 3 of the drawing, I have shown a modification in which I substitute for the racket-shaped portion *a*, a solid body portion *d* having a handle *d*² and made from a 65 board or other suitable material, and with this exception the modification shown in Fig. 3 is constructed and operated in playing the game in the same way as is the construction shown in Figs. 1 and 2.

75

In playing the game, the handle of the body portion is grasped in one hand and the ball held in the other, and said ball is thrown upon the floor, ground or pavement with sufficient force to cause it to bound upwardly, and in its descent the ball may be caught in one of the ball receptacles of the device, and said ball receptacles may be given different numbers and a player may have any desired number of plays, and any desired number may play the game, and the number of the receptacle in which the ball is caught will be counted by the player, and the player winning the greatest number of 80 points will win the game, the numbers of the ball receptacles may be placed on said receptacles, if desired, or they may be placed on a score card having a picture of the device, but my invention is not limited to any particular method of counting or scoring a 85 game, nor to the exact details of construction herein shown and described, and changes therein and modifications thereof may be made, within the scope of the appended 90 claims, without departing from the spirit of 95 my invention or sacrificing its advantages.

The object of using a tennis racket in the construction of my improved game device is to provide means whereby those possessing such rackets may play my improved game 100 without the necessity of providing anything except the cage proper, but it must be understood, as hereinbefore set out, that any suitable form of a body part having a handle and to which the cage proper may be secured, may be employed, and in this way an 105 entirely new game device provided.

110

Having fully described my invention, what I claim as new and desire to secure by Letters Patent, is:-

1. In a game device of the class described, 5 a body portion provided with a ball cage member and forming in connection with the body portion ball receptacles adapted to receive a ball, said cage member having rotatably mounted legs by which it may be detachably connected with the body portion.
2. The herein described attachment for 10 tennis rackets comprising a ball cage member adapted to be detachably connected with the body portion of the racket and to form in connection therewith ball receptacles of which said body portion forms the bottom.
3. The herein described attachment for 15 tennis rackets comprising a ball cage member forming in connection with said body

portion receptacles adapted to receive a ball, 20 said cage member being provided with legs which are rotatably connected therewith and may be detachably connected with the body portion.

4. A game device of the class described 25 comprising a body portion and a cage member, devices foldably connected with said cage member and adapted to be detachably connected with the body portion to support said cage member parallel therewith.

In testimony that I claim the foregoing as my invention I have signed my name in presence of the subscribing witnesses this second day of February, 1921.

CHARLES T. STEWART.
